FIG.10

FIG.11

FIGURE 1 is a rear perspective view of a typewriter desk embodying my new design;

FIGURE 2 is a front elevational view thereof;

FIGURE 3 is a left end elevational view thereof;

FIGURE 4 is a right end elevational view thereof;

FIGURE 5 is a rear elevational view thereof;

FIGURE 6 is a bottom plan view thereof;

FIGURE 7 is a front perspective view of a modified form of the desk shown in FIGURE 1, with a central platform positioned for receiving a typewriter, and wherein the book box is disposed with its longer dimension vertical instead of horizontal as in FIGURE 1, and wherein the desk top is proportionately shorter from end-to-end than the top in FIGURE 1, all as shown;

FIGURE 8 is a rear elevational view thereof;

FIGURE 9 is a left end elevational view thereof;

FIGURE 10 is a right end elevational view thereof; and

FIGURE 11 is a bottom plan view thereof.

I claim:

The ornamental design for a typewriter desk, substantially as shown and described.
